TWO-STAGE FLUID PUMPS

Frank Guy Mattos, Hayes, England, assignor, by mesne assignments, to Fairey Aviation Limited, Hayes, England, a company of Great Britain

Filed Apr. 26, 1956, Ser. No. 580,822

Claims priority, application Great Britain Apr. 26, 1955

5 Claims. (Cl. 103—38)

The invention relates to two-stage fluid pumps and one object is to provide an efficient high speed pump capable of meeting changes in demand.

According to the present invention, a multi-cylinder variable-angle swashplate fluid pump comprises a casing, a rotatable driving shaft extending through the casing, a pair of opposed swashplates mounted in spaced alignment on the driving shaft for rotation therewith within the casing, each of the swashplates being pivoted about a tilting axis transverse to the shaft axis, cylinder means fixedly mounted within the casing and affording two groups of pumping plungers of which each group is circumferentially disposed around the shaft axis in operative engagement with the face of one of the swashplates for actuation thereby, and angle-adjusting mechanism operable to vary the angle of tilt of both the swashplates simultaneously by tilting them in opposite directions about their transverse tilting axes, the said angle-adjusting mechanism comprising a hydraulic jack mounted on the driving shaft for rotation bodily with the swashplates and engaged between opposed peripheral portions of the two swashplates to apply oppositely directed tilting forces thereto, the jack being supplied with pressure fluid from a non-rotary source. The said means may include a pilot valve element within a shaft carrying the swashplate and acted on by the output pressure to move in response to changes in the output pressure to admit output pressure to an actuator rotatable with the swashplates, for varying the swashplate angle, for example by means of a cam acting on the swashplates.

Preferably the pivot axis of the swashplate is offset from the centre of rotation of the plate away from the surface where the cam acts on the plate in order that a resultant torque about the hinge axis shall tend always to keep the swashplate against the cam.

The invention may be carried into practice in various different ways and one specific embodiment will be described by way of example with reference to the accompanying drawings, of which:

Figure 1 is a longitudinal cross-section through a two-stage fluid pump intended to run at about 6000 r.p.m.,

Figure 2 is a diagrammatic view similar to Figure 1 and showing the route followed by the fluid, and

Figure 3 is a perspective view, partly broken away, of the hydraulic actuator for varying the angle of the swashplates in the second stage, and

Figure 4 is a sectional plan of the hydraulic actuator of Figure 3.

The pump has a non-positive centrifugal first stage constituted by an impeller 11 mounted on the main shaft 12 which is driven from the left hand end as seen in Figure 1. The second stage is constituted by a pair of swashplates 13 and 14 mounted to rotate with the shaft 12 and each associated with seven reciprocators arranged around the shaft 12 adjacent the outer surface of the

2

plate. As can best be seen in Figure 2, the swashplates 13 and 14 are pivotally mounted about a transverse axis 15 a little to one side of the axis of the shaft 12 so that they can be moved between a position in which they are perpendicular to the axis of the shaft 12 and a position in which they make a smaller angle with the axis of the shaft. In Figures 1 and 2 the swashplates are shown in an intermediate position.

Each swashplate reciprocator consists of a fixed cylinder 21 fitted in the casing 22 of the pump and a piston 23 constituted by a slideable telescoping tube which has a hollow hemi-spherical cup 25 interposed between a corresponding seat in the closed end of the piston 23 and the surface of the swashplate. The ends of the piston and the cup 25 are bored to allow fluid pressure in the cylinder 21 to act against the face of the swashplate and effect a pressure balance. The cup 25 is maintained in contact with the swashplate, and the piston 23 in contact with the cup by means of a spring 27 surrounding the piston and interposed between a fixed part and an annular external flange 24 at the closed end of the piston. A pin 26 serves to prevent the cup 25 from moving more than a short distance away from its seat in any circumstances. Alternatively a positive means of connecting the piston to the swashplate may be used particularly at high speeds.

As it is well understood, the swashplate stage operates as the swashplates rotate to produce a reciprocating or pumping action of the pistons 23 in the cylinders 21. The stroke varies from zero when the plate is perpendicular to the axis of the shaft 12 to a maximum when the plate is inclined at the minimum angle to the shaft axis.

Fluid is drawn into the pump through an opening 31 in the right hand end on the axis of the pump which leads to the input of the impeller 11 around an ogival boss 32 held in position within the opening 31 by three radial ribs 33. In the first stage the fluid is raised to a pressure of about 90 lbs. per square inch, and it travels by way of a passage 34 to a swashplate chamber 35 which surrounds the shaft 12. Equally circumferentially spaced in each end wall of the swashplate chamber 35 are seven valves 36 leading each to one of the cylinders 21 through a circumferential passage.

Each valve 36 is a non-return valve having an opening normally closed by a diaphragm 37 under the action of a compression spring 38. On the suction stroke of each piston 23 the pressure drop across the valve 36 allows fluid to flow from the swashplate chamber 35 to the inlet 39 of the corresponding cylinder 21.

The outlet from the cylinder 21 is controlled by a similar non-return valve 42 which is biased by a spring 43 to be closed as long as the pressure on its outlet side is greater than the pressure in the cylinder 21. Thus after fluid has been introduced into the cylinder 21, on the compression stroke of the piston 23 fluid is raised to a pressure of about 4000 lbs. per square inch at which the valve 42 opens to admit high pressure fluid to a passage 44 which leads by way of an annular chamber 45 to a radial outlet passage 46. The outlets from the seven cylinders associated with the left hand swashplate 14 lead directly to the outlet 46 but those from the seven cylinders associated with the right hand swashplate 13 lead to the outlet 46 by way of a radial passage 47 and a longitudinal passage 48.

The machine for controlling the angle of the swashplates is operated hydraulically through the shaft. Thus the shaft 12 runs in ball bearings 51 and 52 held in housings formed in the casing 22 and at its right hand end

is splined to an auxiliary shaft 53 which in turn is splined to a sleeve 54 mounted to rotate in ball bearings 55 held in the casing 22. The sleeve 54 has a central hole 55 which leads to a longitudinal bore 56 in the auxiliary shaft 54 and this in turn leads to a chamber 57 in the end of the main shaft 12 into which is screwed a sleeve 58 having a central bore containing a pilot valve element 59 which is normally biased towards the right in Figure 1 by means of a pin 61 and a compression spring 62 acting between the left end of the chamber 57 and a flange 63 formed on the pin 61.

From the radial passage 47 a small passage 65 leads by way of a radial passage 66 to a chamber 67 formed in the ogival boss 32 positioned within the inlet to the impeller 11 so that fluid at substantially the outlet pressure from the second stage is admitted through the hole 55 and the bore 56 into the chamber 57 within the shaft 12.

The right hand end of the sleeve 58 is closed by a bung 71 screwed into it while the sleeve 58 itself is held in position by being screwed into a threaded counterbore 72 formed within the shaft 12. The thread has circumferential discontinuities providing longitudinal passages arranged around the sleeve 58 to admit fluid from the chamber 57 to a central longitudinal bore 74 in the pilot valve element 59 by way of a fluid passage 75 formed in the sleeve 58 and a circumferential recess 56 near the right hand end of the element 59. The net effect of the fluid in this bore 74 is to balance the thrust of the spring 62 when the outlet pressure is at the desired value and in this condition the element 59 is in the position shown in Figure 1.

It will be seen that the sleeve 58 has two circumferential ports 81 and 82 communicating with an actuator 83 to be described in more detail below. These ports 81 and 82 are normally closed by lands 84 and 85 formed on the pilot valve element 59 and it can be seen that if the outlet pressure from the swashplate second stage increases or decreases the pilot valve element 59 will be moved to the left or to the right to admit pressure fluid to one or other of the ports 81 and 82.

The actuator 83 is shown diagrammatically in Figures 3 and 4 and comprises a cylindrical socket 91 formed integrally with the shaft 12 and provided with two diametrically opposed inwardly projecting walls 92 between whose inner ends is positioned the shaft 93 of a butterfly piston which can turn in journals formed in platens 97 and 98 at either end of the socket 91 as shown in Figure 1. The wings 94 and 95 of the butterfly are positioned one in each of the two sector-shaped chambers 99 and 100 into which the interior of the socket 91 is divided by the walls 92. The two ports 81 and 82 lead into the chamber 100 as seen in Figure 4, one on either side of the piston wing 95, and the shaft 93 has two non-intersecting diametrical bores 96, each of which serves to transmit fluid from one chamber on one side of the wing 95 to the corresponding chamber on the opposite side of the wing 94 so that it acts differentially on both wings 94 and 95 and can rotate the piston. The upper end of the shaft 93 has secured to it an oval shaped cam 101 which is in contact with two lugs 102 (Figure 1) one on each of the swashplates 13 and 14 so that as the shaft 93 is turned the cam 101 will force the swashplates further apart or allow them to come nearer together so as to vary the swashplate angle of both swashplates simultaneously in opposite directions and in consequence regulate the quantity of fluid delivered by the swashplate stage.

As has been already described the swashplates pivot about an axis 15 displaced on the other side of the axis of the shaft 12 from the cam 101 and this ensures that during operation those cylinders 21 which are on their compression stroke have a net torque tending to urge the swashplates into contact with the cam 101. The same

effect is achieved when the pump is stationary by means of a plunger 104 which can slide in a radial socket 105 formed in the shaft 12 and which is urged outwards by means of a compression spring 106 into contact with ears 107 formed on the two swash plates so that the spring always tends to move the plunger 104 in the direction to move the two ears 107 apart and thus hold the lugs 102 in contact with the cam 101.

It will be seen that any variation in the outlet pressure from the second stage, for example due to a change in demand on the pump, by moving the pilot valve element 59 operates the hydraulic actuator 83 to turn the cam 101 and thus to vary the angles of the swashplates 13 and 14 to change the quantity of fluid pumped per cycle in the sense to compensate for the change in pressure.

By virtue of the first stage 11 being a non-positive stage, i.e., a stage which does not pump a specified quantity of fluid per cycle but whose quantity pumped depends upon the demand, no means is required to compensate for changes in the demand from the second stage while the centrifugal stage can operate at high speed and therefore fairly efficiently. Since most of the power developed in the second stage, the relatively low efficiency of the first stage is not very noticeable. Controlled bleed orifices can be arranged to dissipate heat losses in the first stage when it is not pumping fluid.

Finally it is pointed out that by mounting two swashplates back-to-back the resultant axial lead on the shaft is balanced while since the means for adjusting the swashplate angle in accordance with the outlet pressure is contained within the shaft 12, no thrust bearing is required as would be the case if the swashplate angle were adjusted by a non-rotating member.

The characteristic of the pump at 6000 r.p.m. is such that 18 gallons can be pumped per minute with a 4° swashplate angle, while at an angle of 2½°, this rate of pumping is approximately halved. Thus a small change in the angle can compensate for quite a large change in demand.

What I claim as my invention and desire to secure by Letters Patent is:

1. A multicylinder variable-angle swashplate fluid pump which comprises a casing, a rotatable driving shaft extending through the casing, a pair of opposed swashplates mounted in spaced alignment on the driving shaft for rotation therewith within the casing, each of the swashplates being pivoted about a tilting axis transverse to the shaft axis, cylinder means fixedly mounted within the casing and affording two groups of pumping plungers of which each group is circumferentially disposed around the shaft axis in operative engagement with the face of one of the swashplates for actuation thereby, and angle-adjusting mechanism operable to vary the angle of tilt of both the swashplates simultaneously by tilting them in opposite directions about their transverse tilting axes, the said angle-adjusting mechanism comprising a hydraulic jack mounted on the driving shaft for rotation bodily with the swashplates and engaged between opposed peripheral portions of the two swashplates to apply oppositely directed tilting forces thereto, the jack being supplied with pressure fluid from a non-rotary source.

2. A pump as claimed in claim 1 including a servo valve disposed within a bore in the driving shaft and in fluid communication with said jack and being arranged to control the operation of the hydraulic jack.

3. A pump as claimed in claim 2 in which the hydraulic jack comprises a rotary jack spindle driven by a hydraulic motor and a cam mounted on the jack spindle, the cam having duplicate cam surfaces respectively in camming engagement with the said opposed peripheral portions of the two swashplates.

4. A pump as claimed in claim 3 in which the transverse tilting axis of each swashplate is off-set from the

axis of the driving shaft on the opposite side thereof from the said peripheral portions of the swashplates engaged by the cam.

5. A pump as claimed in claim 3 in which the hydraulic jack comprises a jack cylinder carried by the driving shaft and rotatable therewith, the axis of the cylinder being at right angles to that of the driving shaft, a vane-type rotary piston mounted on the jack spindle within the casing, and inlet means controlled by the servo valve and arranged to admit hydraulic pressure fluid into the jack 10 cylinder differentially on opposite sides of the piston to rotate it together with the jack spindle and thereby to rotate the cam.
